TURNBUCKLE FOR JACK PUMPING SYSTEMS

Donald W. Auld, Bartlesville, Okla., assignor to Phillips Petroleum Company, Bartlesville, Okla., a corporation of Delaware

Application May 15, 1933, Serial No. 671,233

1 Claim. (Cl. 74—586)

The present invention relates to apparatus primarily intended for use in connection with oil well pumping systems wherein a number of wells are operated from a central power plant by means of surface pull lines between the wells and power, and has particular reference to pumping systems such as described in an application by Thomas E. Hindman filed May 5, 1933, Serial No. 669,597, and relating to a "Method and apparatus for the 10 maintenance and operation of jack pumping systems".

In the system of pumping a plurality of oil wells by the use of a single band wheel power, considerable trouble is encountered due to expansion and contraction of the pull lines which connect the central power with the individual pumping jacks. This expansion and contraction, due to changes in surface temperatures, causes the pumping jacks, sucker rods, and pump plunger together with its cups to operate in varying zones. With a rise in surface temperature, resulting in expansion of the pull line, the plunger and cups will operate in a zone low down in the working barrel permitting the upper part of the working barrel to be corroded to a degree depending upon the corrosiveness of the oil being pumped, whereas with a fall in surface temperature, resulting in contraction of the pull line, the plunger and cups will operate in a zone high up in the working barrel so that the cups contact with the corroded inner surface of the working barrel and are subjected to excessive wear.

It is therefore the primary object of the present invention to provide an improved form of device adapted to be interposed in surface pull lines to automatically compensate for expansion and contraction in the line and thereby insuring travel of the pump plunger in the same zone of contact in the working barrel.

A further object of the invention is to provide 40 a device for automatically compensating for expansion and contraction due to temperature changes, in any reciprocating rods employed for transmitting power for a considerable distance and wherein it is essential that the operated mechanism operate without variance in its movement.

Other objects and advantages of the invention will be apparent during the course of the following detailed description, taken in connection with the accompanying drawing, forming a part of 50 this specification and in which drawing:—

Figure 1 is a top plan view of the device shown connected in a pull line.

Figure 2 is a top plan view of the device shown in its opposite position of movement from that 55 shown in Figure 1.

Figure 3 is a view in side elevation showing one of the ratchets engaging its pawl to extend the pull line after having been contracted due to a lowering of temperature along the pull line.

Figure 4 is a view in side elevation showing one of the ratchets engaging its pawl so as to automatically contract the pull line after having been elongated due to a rise in temperature along the pull line.

Referring to the drawing in detail, wherein similar reference characters designate corresponding parts throughout the several views, the apparatus is intended to be interposed in a pull line and serve as a portion thereof in such manner as to automatically compensate for expansion and contraction in the line due to changes in surface temperature.

The device which is mounted adjacent one end of the pull line and preferably near the pumping jack, comprises a substantially flat base or stand A which may be formed of metal or any other suitable material. The base A may be rigidly mounted in place upon a suitable foundation so as to extend longitudinally of the path of reciprocatory movement of the pull line and provide means for guiding of the pull line coupling sections B and C, as well as the means D acting to automatically compensate for any expansion and contraction in the pull line at either side of the device. The coupling section B is preferably coupled to the pull line running to the source of power, while the coupling section C is coupled to the usual rod or stirrup which is attached to the pumping jack.

The base A is provided at one end of its body portion 5 with an offset 6 and at its opposite end with an offset 7, and these offsets respectively support standards 8 and 9, the standard 8 being provided at its upper end with a slide way 10 and the standard 9 is provided at its upper end with a slide bearing 11. The coupling section B is provided at one end with a U-shaped cross head 12 embodying parallel arms 13 which are reciprocally guided in the slide way 10, and connecting the arms at one end is a crosspiece 14 providing a nut having its screw threaded bore extending parallel to the arms 13. The coupling section C which is reciprocally guided in the bearing 11 in axial alignment with the cross head 12, is provided at its inner end with a coupling head 15 which is substantially D-shaped and providing a crosspiece 16. This crosspiece 16 is provided with a circular opening 17 which is co-axial with the axis of the coupling section C.

The pull line coupling sections B and C are connected by an adjustable coupling member E automatically operated by the means D to compensate for any expansion and contraction in the pull line. This coupling member E is formed with screw threads 18 at one end for threading into the nut 14 and has its plane shank portion 19 rotatable in the opening 17 and provided with a head 20 for engaging the inner side of the crosspiece 16 whereby a swivel coupling is formed between one end of the coupling member E and the pull line coupling section C. Thus it will be seen that upon rotation of the coupling member E in one direction, the spacing between the nut 14 and coupling head 15 may be increased, while upon rotating the coupling member in an opposite direction, the spacing between the nut 14 and coupling head 15 may be decreased.

The coupling member E is automatically operated by the means D, and this automatic operation is accomplished whenever the coupling member is moved in either direction beyond a given path of movement. The means D comprises a crosshead 22 reciprocally guided between guide rails 23 mounted upon the base body portion 5 to extend parallel to the line of reciprocatory movement of the pull line. Carried by the crosshead 22 is a standard 24 providing a bearing for a shaft 25 journaled to extend at a right angle to the axis of the coupling member or shaft E. Rigidly secured to the outer end of the shaft 25 is a pair of inner and outer ratchet wheels 26 and 27 respectively having the teeth thereof oppositely arranged as shown in Figure 3. Keyed or otherwise secured to the inner end of the shaft 25 is a bevel gear 26 for meshing with a bevel gear 29 fixed on the coupling shaft E.

Carried by the base A adjacent opposite ends of the slide way for the crosshead 22 is a pair of ratchet arms or pawls 30 and 31 which respectively co-act with the ratchet wheels 26 and 27 to impart rotation to the shaft 25. These ratchet arms are mounted upon posts 32 by means of bolts 33 extended thru slots in the ratchet arms to permit for adjustment of the ratchet arms longitudinally of the base A.

Carried by or formed integral with the standard 24 is an angular bracket arm 35 having its arm 36 connected to the shaft E at the plane portion 19 of the shaft. The shaft portion 19 may be provided with a collar 37 operating in a bearing 38 formed at the end of the arm 36 whereby the coupling shaft is free to rotate. This manner of connecting the standard 24 to the shaft E retains the bevel gears 28 and 29 in mesh and also causes the standard to reciprocate with the pull line.

In use of the device, the pawls 30 and 31 are

first adjusted so as not to be engaged by their respective ratchet wheels 26 and 27 during reciprocation of the pull line. So long as an average or mean temperature exists and there is no material degree of expansion or contraction of the pull line, the ratchet wheels will not contact the pawls. However, if there is a considerable drop or fall in temperature so that the pull line is contracted, the ratchet wheel 27 will engage its pawl 31 whereupon, thru the shaft 25 and bevel gears 28 and 29, the coupling shaft E will be rotated in a direction for increasing the spacing between the nut 14 and swivel coupling head 15 so as to automatically compensate for this contraction in the pull line. When there is a material increase in temperature beyond the mean temperature so that the pull line is elongated to a considerable extent, the ratchet wheel 26 will be engaged by its pawl 30 and the coupling shaft E rotated in a direction to compensate for this elongation of the pull line. The nut 14 is held against rotation by the arms 13 of the cross head 12 and thus permits feeding of the threaded portion 18 into and out of the nut upon rotation of the coupling shaft. The coupling shaft E provides in effect, a turnbuckle coupling having threaded connection at one end and a swiveled connection at its opposite end.

Thus it will be seen that when the apparatus is interposed in a pull line, the apparatus will act to automatically compensate for expansion and contraction in the line due to temperature changes.

Changes in details may be made to the form of invention herein shown and described, without departing from the spirit of the invention or the scope of the following claim.

I claim:

In oil well pumping apparatus, in combination with a surface pull line, a stationary stand mounted adjacent to one end of the line, a coupling section reciprocally guided on the stand for connection with the longer portion of the line, means for preventing rotation of the coupling section, a second coupling section reciprocally guided on the stand in spaced apart axial alignment with the first coupling section, a rotatable coupling member connecting the sections in spaced apart relation and having screw threaded connection with the non-rotatable coupling section and swivel connection with the other coupling section, a guideway on the stand parallel to the pull line, a standard guided in the guideway and connected for reciprocatory movement by the coupling member, a shaft journaled in the standard, bevel gearing between the shaft and coupling member, and ratchet means for imparting rotation of the shaft to compensate for elongation and contraction of the pull line.

DONALD W. AULD.
